[57] CLAIM

The ornamental design for a face shield, as shown and described.

DESCRIPTION

FIG. 1 is a front perspective view of a face shield showing my new design;

FIG. 2 is a top plan view thereof;

FIG. 3 is a right side elevational view of the face shield, the left side being a mirror image thereof;

FIG. 4 is an enlarged sectional view thereof taken on line 4—4 of FIG. 6;

FIG. 5 is a bottom plan view thereof;

FIG. 6 is a front elevational view thereof; and,

FIG. 7 is a rear elevational view thereof.

FIG. 1

FIG. 3
